We claim the ornamental design for an air inlet damper, as shown and described.

DESCRIPTION

FIG. 1 is a bottom perspective view of an air inlet damper in an opened configuration showing the new design in a position of use;

FIG. 2 is a right side view thereof;

FIG. 3 is a left side view thereof;

FIG. 4 is a rear view thereof;

FIG. 5 is a front view thereof;

FIG. 6 is a top view thereof;

FIG. 7 is a bottom view thereof;

FIG. 8 is a bottom perspective view of the air inlet damper of FIG. 1 in a closed configuration showing the new design in a second position of use;

FIG. 9 is a right side view thereof;

FIG. 10 is a left side view thereof;

FIG. 11 is a rear view thereof;

FIG. 12 is a front view thereof;

FIG. 13 is a top view thereof; and,

FIG. 14 is a bottom view thereof.

The broken lines present in all FIG. views illustrate portions of the air inlet damper that are environment and form no part of the claimed design.
